Patented Dec. 26, 1972

225,666

ABRASIVE GRINDING WHEEL INCLUDING ENTRANCEWAY

Johnnie Kuest, P.O. Box 1254, Twin Falls, Idaho 83301

Filed Jan. 25, 1971, Ser. No. 109,757

Term of patent 14 years

Int. Cl. D15—99

U.S. Cl. D37—1

FIG. 1

FIG. 2

FIG. 1 is a top front perspective view of the abrasive grinding wheel including entranceway embodying my new design.

FIG. 2 is a bottom rear perspective view.

I claim:

The ornamental design for an abrasive grinding wheel including entranceway, substantially as shown and described.
